ELECTRICAL SWITCH

Filed April 22, 1931

UNITED STATES PATENT OFFICE

NORMAN B. CHACE, OF CINCINNATI, OHIO

ELECTRICAL SWITCH

Application filed April 22, 1931. Serial No. 531,906.

This invention relates to an improved electrical switch for automatically breaking an electric circuit to an electric motor or other electrically operated device, at a predetermined time or upon predetermined operation of the electrically operated device.

An object of the invention is to provide a simple, compact and durable switch for the purpose stated, the parts thereof being readily accessible for replacement when necessary.

Another object is to provide an electrical switch of the above character that may be operatively coupled directly or indirectly with a moving part of a machine to be controlled thereby.

Another object is to provide a novel type of quick break arrangement in a rotary switch, whereby there is maintained a polished conducting surface, the parts being arranged to decrease arcing and excessive wearing of parts.

A further object is to provide in a device of the character stated, means whereby, upon breaking the electrical circuit, the switch automatically conditions itself for further successive actuations. These and other objects are attained by the means described herein and disclosed in the accompanying drawing, in which:

Figure 1 is an elevational view showing in simple form, one of many applications of the device to practical use.

Figure 2 is a cross-sectional view taken on line 2—2 of Figure 1.

Figure 3 is a cross-sectional view taken on line 3—3 of Figure 2.

Figure 4 is a detail view partly in cross-section and showing a contactor and mounting therefor.

Figure 5 is a detail view of a second contactor and mounting means therefor.

An understanding of the operation of the device illustrated in Figure 1 should render clear the nature of the device of the invention.

In the example shown, 7 indicates generally an electrically operated motor having a shaft 8 arranged to drive any suitable mechanism 9 which is to be intermittently actuated. For the purpose of illustration, there

is shown associated with the motor shaft, a worm 10 engaging a worm wheel 11, the latter having associated therewith a plunger or piston rod 9. It will be assumed that the member 9, upon successive actuations of a switch 12, is moved alternately to the positions shown by full and broken lines 13 and 14, respectively. It is readily apparent that a given number of rotations of the worm 10 is required for effecting movement of the member 9 from its full line position to the dotted line position indicated at 14. In the form of the switch shown in the drawing, the arrangement of parts is such that breaking of a circuit therethrough is effected once in each one-half rotation of the switch actuating shaft 15; consequently, the switch may have its shaft 15 directly coupled with the shaft 16 of the device 9—11, or if desired, the switch actuating shaft may be associated with a suitable gear train 17 designed to impart to the shaft 15 a speed equal to that of the shaft 16.

From the foregoing, it should readily be understood that upon manually closing the motor circuit by means of the switch 12, the motor will be energized for moving the gear 11 through a half rotation, at the end of which predetermined movement the switch, which is indicated generally by the character 18, will operate to break the motor circuit. The arrangement shown in Fig. 1 is such that a repetition of the foregoing operation is secured by manually moving the switch contact 19 from its position in contact with the terminal 20 to a position contacting the second terminal 21 of the switch 12. Breaking of the circuit is always automatically effected by the automatic switch 18. As stated before, arrangements somewhat similar to that of Fig. 1 may be employed for operating many other devices, which require intermittent operation.

The switch proper comprises a body or housing 22 of insulating material, through the base 23 of which extends the switch actuating or cam shaft 15. The shaft is suitably journaled in the base and is rotatable relatively thereto. Keyed or otherwise secured

to the cam shaft is a cam indicated generally by 24.

The switch housing carries a plurality of contactors 25, 26 and 27, which are constantly spring urged toward the periphery of the cam, and each of which is electrically connected to electricity conducting wires, for example, the contactor 25 may be electrically connected in series with the motor 7 by means of the conductor 28, which may constitute one of the line wires from a suitable source of electricity, not shown. The contactors 26 and 27 may have electrical connection with the terminals 20 and 21 of the manually operable switch 12, by means of the conductors 29 and 30, respectively. The movable contact 19 of said switch 12 is electrically connected to one of the line wires 31, and said contact may be selectively moved into engagement with the terminals 20 and 21, either manually or mechanically.

As indicated in Fig. 2, suitable means indicated by the character 32 may be provided for yieldingly urging the contactors into contacting relation with the periphery of the rotatable cam 24, said means may comprise plungers 33 yieldingly projected by means of compression springs 34 housed within a suitable adjustable casing 35. The invention, however, is not to be limited to this form of means for urging the contactors into position on the cam.

The rotatable cam comprises, in its simplest form, two outer substantially parallel portions 34 and 35, hereinafter referred to as contact segment mountings, which may be of any suitable thickness, and held in spaced relation by a spacing means 36. The spacing means is of such dimensions as to render it free from contact with the movable contactors. The spacer, as well as the contact segment mounting means, preferably is of insulating material, and if desired, these three parts may be shaped from a single block of insulation.

Each of the members 34 and 35 has fixed thereon the contact segments 37 and 38 which preferably consist of parts of a true circular ring made of electricity conducting material, for example, brass or copper. Because of the shape of the segment mounting means, the contact segments are eccentric to the cam shaft 15. Opposite ends of the contact segments are unequally spaced from the axis of the cam shaft, and the end closest thereto will hereinafter be termed the heel of the contact segment, while the farthest removed end will be termed the toe thereof. Therefore, the heel and toe of the contact member 38 are respectively indicated at 39 and 40, whereas the heel and toe of the contact segment 37 are indicated respectively by 41 and 42. Each contact segment may be substantially a two-thirds part of a true circular ring and each may be secured on the periphery of a segment mounting means which may be approximate-

ly three-fourths truly circular, the remaining one-fourth part being an arc directed inwardly toward the drive shaft in order to provide the steps 44 and 45. The toe end of each contact segment is secured, and terminates, at its 70 respective step. The peripheral or neutral portions 46, which are located between a toe and heel of each ring segment, is of insulating material.

The contactor 25, as shown in Fig. 3, is of sufficient width to contact with either of the contact segments 37 and 38, but it will be noted that said contactor can at no time simultaneously contact both of them because of the eccentric relation of the contact segments one to the other. This may be clarified by referring to Fig. 2 from which it will readily be apparent that any line drawn parallel with the axis of the cam may include one, but not both, of the contact segments. The steps 44 and 45, the toes, and the heels of the cam segments are located so as to be substantially diametrically opposite to one another, respectively. It should be noted also, that part of the heel of each cam segment extends past or beyond the toe of the other cam segment, and this may be termed an overlapping, though the heels and toes of the cam segments are not in the same plane.

The contactor 26 always follows the periphery of the segment 37 and its mounting means, while the contactor 27 follows the periphery of the segment 38 and its mounting means 34. As shown in the drawing, the contactor 27 is engaging the neutral portion 46, whence, upon further rotation of the cam said contactor will ascend the heel 39 of the segment 38. The circuit cutoffs, however, occur at the step offs rather than at the neutral portions 46, as will be explained in the operation of the device, which follows.

In Figs. 4 and 5 are illustrated the single contactors 26 and 27 and the studs or pivots 47 upon which they are pivotally mounted. One end of each stud may be threaded as indicated at 48 for the reception of nuts or fasteners 49 whereby electrical connection may be made with the conductors 29 and 30. The stud 50 which provides a pivotal mounting for the contactor 25 is similar to those indicated at 47. The switch housing may be provided with a flange 70 or other suitable means for mounting of the switch upon a support.

The operation of the device is as follows. Reference is made to Fig. 2 which shows the relative positions of the parts as they are found during operation of the motor 7. The wide or double contactor 25 is seen to be in contacting relation with the conductor segment 37, while the contactor 26 is resting upon, and making electrical contact with, the same segment 37. The current flow, therefore, is through the circuit comprising the conductors 31, 19, 29, 26, 37, 25, 28 and 61,

which includes the motor 7 and which motor is now rotating the cam-shaft 15 and the cam 24, in the direction of rotation indicated. When the step 45 reaches and then passes the contactor 25, thereby permitting it to drop and break contact with the segment 37, the above circuit immediately becomes broken at 25, for the reason that the contactor 25 at that time is on one segment 38 whereas the contactor 26 is on the other segment 37, these segments being electrically insulated from one another. By the time the contactor 25 has dropped down onto segment 38, the contactor 27 will have climbed onto the heel 39 of segment 38 also, due to rotation of the cam. It will be apparent, therefore, that to restart the motor 7 it is necessary only to pass current through the contactors 27 and 25 and segment 38. This is accomplished by simply throwing the movable switch contact 19 into contact with the terminal 21, thereby completing the circuit through conductors 31, 19, 30, 27, 38, 25, 28 and 61, which includes the motor 7. This circuit will become broken as soon as the contactor 25 leaves the toe 40 of segment 38, at the step-off 44, thereby again stopping the motor. The contactor 26 will have, by that time, reached the heel 41 of the segment 37 on which the contactor 25 is then resting. Upon again throwing the switch arm 19, the motor will again be energized and the parts will assume the relative positions indicated in Fig. 2.

From the foregoing it will be apparent that the motor 7 is automatically stopped at approximately each half rotation of the cam 24; and it should be understood that the speed of cam rotation may be varied, whereby various automatic circuit cut off problems can be solved. The device may be modified for controlling more than one circuit, by adding thereto cams and contactors, and provision may be made for controlling the current of a three wire system of electrical power transmission.

It is to be understood, therefore, that various modifications and changes in structural details of the device may be made, within the scope of the appended claims, without departing from the spirit of the invention.

What is claimed is:

1. A rotary electrical contact member for an electrical control switch comprising a plurality of insulated similar electricity conducting segments at least two of which are greater than a half circle in peripheral extent, the segments being eccentric to the axis of rotation of the rotary contact member and having separated toe and heel portions overlapping but at different distances from the axis of rotation of the rotary contact member.
  2. In a device of the class described the combination of a rotatable member including two spaced curved electricity conducting segments and three electricity conducting con-
- tactor means associated therewith, said segments being insulated from one another and disposed within parallel planes eccentrically to the axis of rotation of the rotatable member and providing step offs whereby an electrical circuit may be broken and another electrical circuit may be closed, the electricity conducting contactor means being yieldingly urged toward the segments and one of which contactor means is sufficiently wide to ride upon both segments in succession and the others of which ride respectively upon the segments during rotation of the rotatable means, rotation of the rotatable means serving to move the step offs past that contactor means which rides successively upon both segments.
3. In a device of the class described the combination of a rotatable member including two spaced curved electricity conducting segments and three electricity conducting contactor means associated therewith, said segments being greater than a half circle in length and insulated from one another and disposed within parallel planes eccentrically to the axis of rotation of the rotatable member and providing step offs whereby an electrical circuit may be broken and another electrical circuit may be closed, the electricity conducting contactor means being yieldingly urged toward the segments and one of which contactor means is sufficiently wide to ride upon both segments in succession and the others of which ride respectively upon the segments during rotation of the rotatable means, rotation of the rotatable means serving to move the step offs past that contactor means which rides successively upon both segments.
4. In a device of the class described the combination of a rotatable member including two spaced curved electricity conducting segments and three electricity conducting contactor means associated therewith, said segments being of true circular arc formation greater than a half circle in length and insulated from one another and disposed within parallel planes eccentrically to the axis of rotation of the rotatable member and providing step offs whereby an electrical circuit may be broken and another electrical circuit may be closed, the electricity conducting contactor means being yieldingly urged toward the segments and one of which contactor means is sufficiently wide to ride upon both segments in succession and the others of which ride respectively upon the segments during rotation of the rotatable means, rotation of the rotatable means serving to move the step offs past that contactor means which rides successively upon both segments.
5. A rotary electrical switch unit having in combination a rotary electrical contact member comprising a plurality of insulated similar electricity conducting segments at

least two of which are greater than a half circle in peripheral extent, the segments being eccentric to the axis of rotation of the rotary contact member and having separated 5 toe and heel portions overlapping but at different distances from the axis of rotation of the rotary contact member, a plurality of electricity contactor means yieldingly urged toward the segments and exceeding the segments in number, one of said yieldingly urged 10 contactor means being sufficiently wide to engage two of the segments and arranged to contact said two segments in succession.

6. A rotary electrical switch unit having in 15 combination a rotary electrical contact member comprising a plurality of insulated similar electricity conducting segments both of which are greater than a half circle in peripheral extent, the segments being eccentric 20 to the axis of rotation of the rotary contact member and having separated toe and heel portions overlapping but at different distances from the axis of rotation of the rotary contact member, a plurality of electricity contactor means yieldingly urged toward the segments and exceeding the segments in number, one of said yieldingly urged contactor means being sufficiently wide to engage two of the 25 segments and arranged to contact said two segments in succession and mounting means for the contactor means arranged in a circle arc about and spaced from the periphery of the rotary member.

7. In a device of the class described the 30 combination of a rotatable member including two spaced curved electricity conducting segments and three electricity conducting contactor means associated therewith, said segments being insulated from one another and 35 disposed within parallel planes eccentrically to the axis of rotation of the rotatable member and providing step offs whereby an electrical circuit may be broken and another electrical circuit may be closed, the electricity 40 conducting contactor means being yieldingly urged toward the segments and one of which contactor means is sufficiently wide to ride upon both segments in succession and the others of which ride respectively upon the 45 segments during rotation of the rotatable means, rotation of the rotatable means serving to move the step offs past that contactor means which rides successively upon both segments and mounting means for the contactor 50 means arranged in a circle arc about and spaced from the periphery of the rotary member.

In testimony whereof, I have hereunto 55 subscribed my name this 18th day of April, 1931.
NORMAN B. CHACE.
